UNITED STATES PATENT OFFICE.

EPHRAIM E. BUCKNER, OF OWOSSO, MICHIGAN, ASSIGNOR OF ONE-FOURTH TO CARL SCHLOSSOW, OF SAGINAW, MICHIGAN.

CUTTING BLOCK.

1,404,831.

Specification of Letters Patent. Patented Jan. 31, 1922.

Application filed August 29, 1921. Serial No. 496,285.

To all whom it may concern:

Be it known that I, EPHRAIM E. BUCKNER, a citizen of the United States, residing at Owosso, in the county of Shiawassee and 5 State of Michigan, have invented certain new and useful Improvements in Cutting Blocks, of which the following is a specification, reference being had to the accompanying drawings.

10 This invention relates to certain improvements in cutting blocks and has relation more particularly to a device of this general character which is adapted to be used in connection with the cutting of auto top 15 curtains, seat coverings, harness and other leather work and which is also adapted to be used by tailors and by butchers.

It is an object of the invention to provide 20 a novel and improved block of this general character of a knock-down type and which comprises a plurality of sections or members which have coacting therewith means whereby said sections or members may be effectively maintained in assembled relation.

25 Another object of the invention is to provide a novel and improved device of this general character embodying a plurality of separable members or sections assembled in a manner whereby said members or sections 30 may be reversed when desired in order to maintain the upper or working surface of the block substantially smooth or finished.

The invention consists in the details of 35 construction and in the combination and arrangement of the several parts of my improved cutting block whereby certain important advantages are attained and the device rendered simpler, less expensive and otherwise more convenient and advantageous for use, as will be hereinafter more 40 fully set forth.

The novel features of my invention will hereinafter be definitely claimed.

In order that my invention may be the 45 better understood, I will now proceed to describe the same with reference to the accompanying drawings, wherein:

Figure 1 is a view in side elevation of a 50 block constructed in accordance with an embodiment of my invention;

Figure 2 is a horizontal sectional view taken substantially on the line 2—2 of Figure 1;

Figure 3 is a fragmentary sectional view

taken substantially on the line 3—3 of 55 Figure 2;

Figure 4 is a view in top plan of the block as disclosed in Figure 1;

Figure 5 is a view in perspective, with a portion broken away, of one of the corner 60 members or sections;

Figure 6 is a view in perspective of one of the intermediate blocks or members;

Figure 7 is a fragmentary view in elevation illustrating a slightly modified form 65 of invention; and

Figure 8 is a view in elevation of one of the tie or connecting bolts.

As disclosed in the accompanying drawings, B denotes a block in its entirety 70 constructed in accordance with an embodiment of my invention and which block is of a type especially designed and adapted for use by butchers or other work wherein the block is subjected to relatively heavy blows. While 75 the block as particularly illustrated in Figure 4 is oblong in top plan, I wish it to be understood that I do not limit myself to this particular design as the same can be assembled with different configurations. 80

The block B comprises a plurality of members or sections 1 preferably of wood and square in cross section. Each of the sections or members 1 at substantially its longitudinal center is provided therethrough 85 with a pair of openings 2, said openings being perpendicularly related and slightly spaced apart in a direction longitudinally of the section or member 1.

The inner end portion of each of the openings 2 is enlarged, as at 3, to provide a chamber or pocket in which is adapted to be housed a coupling nut or member 4. The openings 2 through the outer members or sections 1 have their outer end portions 5 95 also enlarged to receive and house a holding member or nut 6.

The members or sections 1 are of substantially the same length with the exception of the corner members or sections and 100 which corner members or sections are provided with the extensions 1^a so that said corner members or sections may serve as supporting legs to maintain the block B proper at a desired elevation. 105

Extending through each of the openings 2 is a tie bolt 7 threaded at its opposite end portions so that an end portion of a bolt 7

may be properly engaged within a coupling nut or member 4 or have engaged therewith a holding member or nut 6. The coupling members or nuts 4 and the tie bolts 7 coat 5 in a manner whereby the various members or sections 1 are effectively held or clamped in assembled relation. The maintenance of the outer or side sections 1 in applied position is effected through the instrumentality 10 of the holding members or nuts 6.

At desired intervals and preferably at locations in staggered relation, I find it of particular advantage to employ the locking plates 8 preferably of metal and each of 15 which plates is arranged in interlocking engagement with four adjacent sections or members 1 at the corners thereof, each of such members or sections 1 being provided in its corner portion with a groove 9 to receive a marginal portion of a plate 8. The locking plates 8 serve to hold the sections or members 1 firmly in place while the same are being drawn together by the tie bolts 7 to prevent the sections or members 1 from 25 having relative endwise movement, thereby insuring a perfectly smooth top or working surface at all times.

I also find it of particular advantage to seat within each of the chambers or recesses 30 5 in the outer or side members or sections 1 a cup-shaped washer 10 to receive the adjacent holding member or nut 6.

The particular construction herein disclosed for maintaining the sections or members 1 in assembled relation permits the same to be readily reversed or turned over when the working or upper surface of the block B becomes unduly worn.

In order that the corner members or sections 1 may be reversed for the same purpose, the extensions 1^a are each also provided therethrough with the perpendicularly related openings 2^a, the same being arranged in accordance with the openings 2 40 in the opposite end portion of the corner section or member, and said openings 2^a are also spaced the same distance from the adjacent or lower end of said corner section or member as the spacing of the first openings 2 from the adjacent or top end of said corner section or member.

In Figure 7, I illustrate a slightly modified form of my invention wherein all of the members or sections 1' are of the same 55 length but of a length materially less than that of the members or sections 1 hereinbefore referred to. These sections 1' are connected in the same manner as the sections 1 but this lighter construction of the block B' 60 is provided for such work as cloth cutting or the like and wherein the block is not sub-

jected to unusually heavy or rough usage. The assembled members or sections 1' are adapted to be supported at a proper elevation in any desired manner and as generally indicated at 11.

From the foregoing description it is thought to be obvious that a cutting block constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A block of the class described comprising a plurality of sections, each of said sections having angularly related openings disposed therethrough, an end portion of each of the openings being enlarged, a coupling member arranged within the enlarged portion of each of the openings, and tie bolts disposed through the openings of one member and engaged with the coupling member carried by an adjacent member.

2. A block of the class described comprising a plurality of sections, each of said sections having angularly related openings disposed therethrough, an end portion of each of the openings being enlarged, a coupling member arranged within the enlarged portion of each of the openings, tie bolts disposed through the openings of one member and engaged with the coupling member carried by an adjacent member, and holding members engaged with the outer end portions of the tie bolts disposed through the side members.

3. A block of the class described comprising a plurality of sections, each of said sections having angularly related openings disposed therethrough, an end portion of each of the openings being enlarged, a coupling member arranged within the enlarged portion of each of the openings, and tie bolts disposed through the openings of one member and engaged with the coupling member carried by an adjacent member, angularly related openings in each section being positioned at substantially the center of said section.

In testimony whereof I hereunto affix my signature.

EPHRAIM E. BUCKNER.
